UNITED STATES PATENT OFFICE.

PETER KUZNOR, OF NEW CASTLE, PENNSYLVANIA.

AUTOMATIC CATCH AND CARRYING MACHINE.

Specification of Letters Patent.

Patented Nov. 7, 1916.

1,203,749.

Application filed April 20, 1916. Serial No. 92,547.

To all whom it may concern:

Be it known that I, PETER KUZNOR, a citizen of Austria, residing at New Castle, in the county of Lawrence and State of Pennsylvania, have invented certain new and useful Improvements in Automatic Catch and Carrying Machines, of which the following is a specification.

My invention relates to improvements in automatic catch and carrying machines, by means of which heavy articles, such as steel plates, etc., may be automatically caught up and carried. I attain this object by the mechanism illustrated in the accompanying drawings, of which—

Fig. 1 is a view in elevation; both sides of the device being exactly alike except on one side are the component parts, N and d, hereinafter more particularly described. Fig. 2 is a view in elevation at right angles to Fig. 1. Fig. 3 is a perspective view below the dotted horizontal line in Fig. 1, between the crossbars H and G, and marked 1—1. Fig. 4 is an enlarged elevated view 20 of the shield E, and its relation to the aperture n. Fig. 5 is a cross section view of Fig. 4, drawn on the dotted vertical line centrally located on said Fig. 4, also, the lower point of one of the hoisting hooks 25 30 C C.

Similar letters refer to similar parts throughout the drawings.

A is a vertical shaft centrally attached to, or mortised in the stationary bar I, and 35 projecting upward inside of the casing, or tube B, and in which it is designed to play freely. This shaft is equipped at its upper end with a transverse stop pin m, projecting into slots a a, in the opposite sides of the 40 tube B, to prevent the shaft from disengaging from said tube when the same is being raised thereon. This casing, or tube B is closed at the top, and is furnished with an eye, f, for means of attaching the same to 45 a crane, or other mechanism, for raising or lowering.

D H I and G are horizontal bars; I and G being firmly attached at their centers to the shaft A, and D and H are movable thereon. The upper sides of G, at its center, are beveled inwardly to the shaft A, forming on either side thereof apertures n n, for the 50 reception of the hoisting hooks C C, (Fig. 2) enabling the latter to catch under the 55 lower side of the bar D, at its center, and raise or lower the same on the shaft A, at

the will of the operator. The said hooks C C, are oblong, and rounded at their lower ends, to enable them to drop freely over the bar D, when the tube B is lowered on the shaft A, and grip under said bar. Said hooks are loosely pivoted at their upper ends in the lugs b b, on said tube.

K K are two horizontal bars centrally attached to the ends of the bar I, and at right angles thereto.

J J J J are gripping jaws centrally pivoted in the ends of the bars K K, and are flared outwardly at their lower points, to prevent their denting or marring the object 70 carried. M M are two tongues, beveled to a point at their lower ends, and mortised in the bars K K at their upper ends, and are intended to serve as back braces to the said jaws when gripping the object to be 75 carried.

E, (Fig. 1;) E E¹, (Fig. 2) are two triangularly shaped shields pivoted at their angles to the stationary blocks F F; the smaller, or right arm of the shield E, (Fig. 80 1) being provided with a knob, or handle, d, the opposite arm of each shield being of sufficient width to cover the apertures n n, and prevent the hoisting hooks C C, from entering and catching underneath the bar 85 D, when not desired in operating the device, as hereinafter more particularly explained. Said shields are connected by means of the cleats e e passing underneath the bar G, to 90 secure their unity of action.

N is a rod, provided with an upper and a lower projecting catch, attached at its upper end to the tube B, and extending downward, in juxtaposition to the knob, or handle d, on said shield E, (Fig. 1) and intended to 95 manipulate said shields E E, as the tube B is raised or lowered on the shaft A, uncovering or covering said apertures n n, as may be desired.

P P P P, (Fig. 1) is a system of levers 100 pivoted to the bars D H and G, and p p p p a like system pivoted in the ends of the bar H, and the upper ends of the jaws J J J J, (Fig. 3.)

These several parts, in combination, operate as follows: To catch and carry: The tube B, with the hooks C C, and rod N, attached thereto, is raised on the shaft A, by means of tackling, or other device, until the transverse stop pin m, in A, is dropped to the lowest point of the slots a a, in B, whereby the lower projecting catch on N 105 110

is brought in contact with the handle *d*, on the shield *E*, and said handle forced upward, throwing the opposite, or broad arms of both shields clear of the apertures *n n*, thus permitting the hooks *C C*, to freely enter said apertures, catch under *D* at its center, and raise the same, vertically, on said shaft, which upward movement of the bar *D* acts reciprocally on the levers *P P P P*, and correspondingly elevates the bar *H*, which in turn, draws upward the levers *p p p p*, pivoted in the ends of the gripping jaws, and forces the lower points thereof inwardly upon the tongues *M M*, firmly gripping the object to be carried. To release the grip, rest the object carried on the floor, or other solid surface, slack the upward tension on *B*, permitting it to drop on the shaft *A*, thereby disengaging the hooks *C C*, from beneath the bar *D*, thus permitting them to hang loosely over the sides of the bar *G*. This downward movement of *B* relieves the upward tension on the levers *P P P P*, and *p p p p*, attached in the manner shown, automatically releasing the grip of the jaws on the object carried. By the same downward movement of *B* the rod *N* is also lowered, bringing the upper catch thereon in contact with the handle *d*, on the shield *E*, carrying the arm to which said handle is attached downward, and forcing the opposite arms of both shields upward, and underneath the lower points of the hooks, covering the apertures *n n*, thereby preventing said hooks reentering said apertures, and again raising the bar *D*, when the tube *B* is raised, as must necessarily be done, to disengage the jaws from the object carried.

40 I am aware that prior to my invention catch and carrying devices, tongs, etc., have been in use having the vertical shaft, levers, movable bars, or sleeves, and flaring jaws, *I*, therefore do not claim such broadly, but

45 I do claim, as new, the following:—

1. The combination in an automatic catch

and carrying machine, of the hoisting hooks *C C*, the movable bar *D*, the stationary bar *G*, located beneath the said bar *D*, and provided with receiving apertures *n n*, on opposite sides thereof, the casing, or tube *B*, provided with slots *a a*, therein, the stationary bar *I*, vertical shaft *A*, the latter mortised centrally at its base in the bar *I*, and having its upper end inclosed in the tube *B*, and equipped with the transverse stop-pin *m*, at its upper end, projecting into said slots in said tube, with the horizontal bars *D* and *H*, acting vertically on said shaft, the stationary bars *G* and *I*, the rod *N*, provided with two catches, the shields *E*, and *E¹*, manipulated by said rod *N*, by means of said catches thereon, in contact with the knob, or handle *d*, on the smaller arm of said shield *E*, the stationary bars *K K*, centrally attached to the ends of said bar *I*, and at right angles thereto, the gripping jaws *J J J J*, pivoted in the ends of said bars *K K*, the tongues *M M*, mortised in said bars *K K*, the systems of levers *P P P P*, and *p p p p*, the first pivoted to the bars *G H* and *D*, the latter to the bar *H*, and the upper ends of said jaws, all as substantially herein described.

2. The combination in an automatic catch and carrying machine, of the blocks *F F*, and the shields *E*, and *E¹*, the manipulating rod *N*, provided with upper and lower catches, in juxtaposition to the handle *d*, on the smaller arm of said shield *E*, for manipulating said shields, *E*, and *E¹*, with the hooks *C C*, the stationary bar *G*, having the apertures *n n*, for the reception of said hooks, the bar *D*, tube *B*, and vertical shaft *A*, all as herein particularly set forth.

In testimony whereof I have affixed my signature in presence of two witnesses.

PETER KUZNOR.
